UNITED STATES PATENT OFFICE.

GIANNI BETTINI, OF PARIS, FRANCE.

YARN SPINNING OR TWISTING APPARATUS.

1,073,022.

Specification of Letters Patent. Patented Sept. 9, 1913.

Application filed August 31, 1910. Serial No. 579,921.

To all whom it may concern:

Be it known that I, GIANNI BETTINI, of Paris, Republic of France, have invented a new and useful Improvement in Yarn Spinning or Twisting Apparatus, which improvement is fully set forth in the following specification, reference being had to the accompanying drawing.

The invention has for its object a special arrangement and a new form of travelers and rings for machines for spinning and twisting the yarn with a view to allowing a much greater speed to be given to the spindles (hence an increase for the output of the machines), to reducing to a minimum the breaking of the yarn during the running of the machines and to obtaining yarns better formed with more regular twist. With this end in view attempts have already been made to replace fixed rings in spinning machines by movable rings, revolving with the travelers, but up to the present none of these rings, which are actuated only by the yarn, has given thoroughly satisfactory results. Their principal defect is that those rings which at the outset revolve perfectly, afterward and in a short time develop an irregular rotation. Frequently they even stop altogether by reason of the fluff which fills the atmosphere of the spinning factories introducing itself between the rings. Furthermore a considerable force is required to rotate these rings which are generally moved by frictional contact with the traveler which is itself moved by the thread. Consequently the thread frequently breaks. By my device the traveler rotates in part by the pull of the thread and in part by the movement of an independent traveler carrier which is caused to rotate by frictional contact with some moving part of the spindle. In the preferred form a light balanced traveler carrier is mounted axially by frictional contact on the spindle and in practice rotates at a speed somewhat slower than the spindle. Furthermore as is well known the thread tension on a spindle varies according to the amount of thread on the bobbin. By my device the tension becomes practically uniform since the thread

is delivered by the traveler constantly close to and at the same distance from the bobbin. The thread also passes through an eye or eyes on the traveler carrier or connected with it and then through the eye of the traveler. By this device uniformity of tension and twist is further obtained.

In the annexed drawings which illustrate by way of example methods of executing the invention, similar letters refer to similar parts.

Figure 1 represents in vertical elevation my new device in the form of a rod to give the traveler greater facility of rotation; this I call my traveler carrier. Figs. 2 and 3 represent special forms of the traveler carrier. Fig. 4 represents a form of my traveler.

In order to facilitate the rotation of the traveler, the latter in any form, for example, that represented in vertical section in Fig. 4 is engaged with a rod A (Fig. 1) of suitable form capable of revolving on the axes *a* and *b*, corresponding to that of the spindle. A rod thus arranged will be able to revolve with the traveler at very high speeds without fear of wear or danger of the factory dust impeding its motion.

In Fig. 1, A represents the rotating rod or traveler carrier, B the traveler capable of sliding along the rod, C any ring fixed or movable suitably fitted to the carriage of the machine, controlling the rise and fall of the traveler along the rod during working; *a* is a cap fitted to the top of the bobbin with a bearing to take the upper point of the rod A and to form an axis of rotation; at *b* the rod terminates in the form of a ring capable of revolving around the foot of the spindle; *f* represents the yarn and O the bobbin. By this arrangement the traveler B will easily be actuated along with the rod A in its rotation by the yarn assisted by the friction of the spindle on the rod at *a* and *b*, thus it will be possible to give much greater speeds to spindles and the stress upon the yarn will be reduced to a minimum.

In order to give the yarn a constantly uniform tension, the arm *m'* bent in any

- suitable way (or any other extension of the traveler) is made to rest against the bobbin in such a way that the guide eye m is a little farther out from the surface of the bobbin.
- 5 As an example of a means for holding the arm m' in contact with the bobbin, I have shown a spring thread or strand P which is approximately parallel to the rod A , being connected to the upper and lower 10 arms thereof and which bears against the arm m' , holding the latter at all times in contact with the bobbin. With a device of this kind, the tension of the yarn will be kept uniform, the force needed for actuating 15 the traveler remaining always the same. The traveler will be able at the same time to slide along the rod A according to the rise and fall of the frame of the machine carrying the ring C , by which it is guided.
- 20 The frame C is operated in the usual way for laying on the thread and the traveler engages with it as shown, or in any other convenient way. It would also be possible not to employ the ring for guiding the traveler, utilizing instead the direct control of 25 the ring carrier frame. To do this it will be necessary only to provide a wider opening between the two wings of the traveler as shown in Fig. 4. This separation being a 30 little wider than the thickness of the frame H , the traveler would enter into the opening intended for the ring, and its wings would fork over the frame to which a polished surface should be given on the friction 35 circumference. During rotation, centrifugal force having a tendency to make the rod A convex, it is only requisite to make this rod slightly concave in its middle portion, as is shown in M (Fig. 2); in this way 40 the rod although yielding to centrifugal force will not pass the limit accorded to it in the space in which it revolves.
- Fig. 3 represents other forms of rod where centrifugal force is better counteracted all 45 around the bobbin. If, on the other hand, it is necessary to retard the rotation of the rod A in relation to the velocity of rotation of the bobbin, it will only be necessary to extend the bottom of the rod at g (Fig. 1) 50 and to fix on this extension any regulating fan W which, according to the inclination given to it, will present more or less resistance to the air and will serve as a drag to assist in reducing the rotation of the rod to the desired speed. The inclination of the fan 55 may be changed according to the quality of the material and the count of yarn to be wound. This fan will further have the property during the rotation of clearing 60 away dust from the neighborhood of the spindles. The fan may be placed in any other suitable position on the rod, or they may be two in number, one in each side of the bobbin to equalize the centrifugal force.

In order to obtain absolute regularity in 65 the twist of the yarn, there may be affixed to the top of the rod a small guide carrier Z having hooks or guides S (Fig. 1) into which the yarn will enter at the outset before arriving at the traveler; thus the torsion will always take place in a given length of the thread, namely between the upper eye S and the fixed eye or guide above (not shown) through which the thread is fed to such upper eye S . The twist will then take 70 place always on the same length of yarn, at the same angle and the yarn will have a uniform twist throughout the bobbin. The guide Z may be adjusted on the top of the rod A so that the arrival angle of the yarn 75 and the twist may be changed by the simple advance or drawing back of the guide on the rod.

Having now particularly described and ascertained the nature of my said invention 85 and in what manner the same is to be performed I declare that what I claim is:

1. In a spinning machine, the combination with a bobbin, of a traveler and a traveler carrier revoluble with the bobbin, the traveler moving loosely along the carrier parallel to the bobbin and having an extension which rests upon the surface of the bobbin during winding, and an eye through which the yarn passes directly to the bobbin and which is held by the extension in constant relation to the surface of the bobbin.

2. In a spinning machine, the combination with a bobbin, a traveler revoluble with the bobbin, and a device for actuating the traveler, of a guide which is offset with relation to the bobbin and which is provided with angularly disposed eyes through which the yarn passes before its arrival at the traveler, and a ring to control the rise and fall of the traveler.

3. In a spinning machine, the combination with a bobbin, a traveler revoluble with the bobbin, and a carrier for the traveler, of a guide mounted on the carrier and through which the yarn passes before its arrival at the traveler, the guide being adjustable toward and away from the axis of rotation of the bobbin, and a ring to control the rise and fall of the traveler.

4. In a spinning machine, a bobbin driven by a spindle, an independent traveler carrier, frictionally driven from the spindle and carrying a traveler capable of independent motion and a thread-guide mounted on said traveler carrier carrying an eye and capable of independent adjustment with reference to the position of the eye of the traveler, substantially as described, and a ring to control the rise and fall of the traveler.

5. In a spinning machine, the combination with a spindle or bobbin and a traveler, of a traveler carrier actuating the traveler and

rotating with relation to the spindle or bobbin, the carrier consisting of a rod which is concavely bent throughout its efficient length, the traveler moving loosely along

5 the carrier parallel to the bobbin and having an extension which rests upon the surface of the bobbin during winding, and an eye through which the yarn passes directly to

the bobbin and which is held by the extension in constant relation to the surface of 10 the bobbin, and a ring to control the rise and fall of the traveler.

GIANNI BETTINI.
